UNITED STATES PATENT OFFICE.

CHARLES E. WILSON, OF HYDE PARK, ILLINOIS.

MOLD FOR BURIAL-CASES.

SPECIFICATION forming part of Letters Patent No. 275,004, dated April 3, 1883.

Application filed April 10, 1882. (No model.)

To all whom it may concern:

Be it known that I, CHARLES E. WILSON, a citizen of the United States of America, residing at Hyde Park, in the county of Cook and State of Illinois, have invented certain new and useful Improvements in Molds for Burial-Cases, of which the following is a specification.

This invention relates to the casting of burial-cases or coffins in an upright position so as to lessen the labor and time required, and obviate the liability of damage attending the turning of the molds and casket after said casket is completed, as is necessary when the casket is cast in an inverted position.

The objects of my invention are to provide the inner surface of the casket or coffin with corrugations or depressions for the purpose of reducing the weight without unduly affecting the strength of the casket; also, to provide a core for the outer mold; so constructed and arranged as to produce the said corrugations or depressions, and at the same time be capable of being readily withdrawn when the casket is completed; and, further, to provide the upper edge of the casket with pieces or strips of metal of a peculiar form to hold the lid-fastening screws and to give strength and stiffness to that part of the casket.

The invention consists in certain peculiarities in the construction, arrangement, and combination of parts, as hereinafter more fully described and claimed.

In the annexed drawings, illustrating the invention, Figure 1 is a plan view of a mold for molding coffins in an upright position. Fig. 2 is a cross-sectional view of the same taken on the line $\alpha\alpha$ in Fig. 1. Fig. 3 is a cross sectional view of a coffin completed; and Figs. 4, 5, and 6 are detail views to be referred to hereinafter.

Similar letters of reference refer to like parts throughout the several views.

A A is the mold, which may be constructed of wood, iron, or any other suitable material.

B is the base-plate or bottom part of the mold, and should be made sufficiently larger than the casket to admit of the side and end walls or outer shell of the mold to rest upon it, and it may be provided with walls or ledges $a a$, equal in height to the desired thickness of the bottom of the casket, thus forming a gage to regulate the thickness of the cement

spread on the base-plate, as and for the purpose hereinafter more fully set forth, or it may be merely a plain surface of the required size. 55

In casting coffins of this class in an upright position the core or inner shell of the mold may be made of suitable material and left in to form a part of the completed casket, or it may be made to be withdrawn in the usual 60 manner, and may be made in sections, or not, as desired. When intended to be withdrawn there are, however, many reasons why a core in sections and collapsible should be preferred. A case so constructed facilitates to a greater 65 degree the process of filling in the cement, is more easily and quickly removed, and it is only by the use of such a core that the inner surface of the core may be provided with corrugations, or with indentures to correspond 70 with projections on the outer surface, which is sometimes desirable.

I make the core C in two or more sections $s s'$, &c., as shown in Fig. 2, the bottom one, s , of which may be a plain-surfaced board or 75 plate, or may have side wall, $a' a'$, as shown, and be provided with openings $o o$, supplied with corresponding pieces, o' , for the purpose of removing the surplus cement from the bottom, should too much be spread thereon, in 80 the manner hereinafter more fully described. The upper sections, $s' s''$, &c., have plain boards or plates b for the side walls, and have their ends composed of two pieces, $b' b''$, hinged at either side to the side pieces, b , in such a 85 manner that they may be folded back parallel with the side pieces, b , as shown in dotted lines in Fig. 1. The end pieces, $b' b''$, are held in position by a bar, b^3 , secured to one of the parts and fitting over staples c in the other, a 90 pin, p , being used to secure them.

The outer shell, A A, of my mold I make in a similar manner to those already in use, composed of the side pieces, $c' c''$, and end pieces, $d d$, held together at the ends by swinging 95 clamps D, composed of two parts, $e e'$, connected by a coupling, e^2 , provided with right and left threads and hinged at one end to one side piece, c' , and provided at the other end with a head, e^3 , which slips into a slot provided 100 for the purpose on the outside face of the other side piece.

For supporting the core C in position in the mold, combination pins or screws may be used,

which go down through the bottom of the core and through the cement into holes provided in the base-plate for them; or these pins or screws may go through the sides of the core into the side walls of the outer shell. I however prefer screws made as shown at E, Figs. 2 and 4, composed of two parts, $f f'$, the lower part, f , of which screws into the base-plate B, and when screwed in to its limits projects above the said plate B a distance equal to the thickness of the bottom of the casket to be made. The upper part, f' , passes through the bottom of the core C and screws into the lower part, f , which is tapped to receive it, the core C resting on and being supported by the lower part, f .

My method of casting a burial-case is as follows: I first spread a thin layer of cement on the base-plate B, then lay upon that a sheet of perforated metal, wire-cloth, or other material intended to strengthen the coffin-walls. This sheet may be of the exact size of the bottom of the core, or larger, and turned out at the edges to lap up around the side walls some distance, and so arranged that it will be embedded within the walls of the cement when the casket is completed. Another layer of cement is then added sufficient to make the required thickness of the bottom of the coffin. The bottom section of the core (or if not made in sections the whole core) is then placed in position upon the screws E and fastened, as before described. If there should be a surplus of cement on the bottom plate, B, the pieces o' are removed from the openings o in the bottom of the core C and the surplus cement allowed to ooze up through said openings as the core is forced down into its position, after which the surplus cement, if any, is removed and the pieces o' replaced. A thin layer of cement having been spread on the side and end walls of the outer shell, and sheets of perforated metal or equivalent placed upon them, as before described for the bottom, they are set up in position and held in place at the bottom by projections upon the outer edge of the base-plate, or by double pins, as shown, and are clamped at the end by clamps D by turning the right-and-left-thread coupling e' . A space between the outer walls and the core still remains to be filled, which is done by pouring or tamping in the cement to the height of the bottom section of the core. The second section is then placed on the first and held in position by double pins, or otherwise, at the sides, and the cement again filled in around it, and so on, if more than two sections are used. When the last section is placed in position and cement put in until near the top, a strip or strips of perforated metal, wire-cloth, or similar material, in a corrugated form, as shown in Fig. 6, is slipped into the cement until the top edge comes flush with the top edge of the completed casket. The pieces of metal n , designed to hold the lid-fastening screws, and provided with projections n' , (see Fig. 5,) which serve as anchors to hold them firmly in the cement,

and also serve as guides to secure their coming in the center of the walls by extending on either side to the shell of the mold, are then placed in position at the proper places and cement is filled in until the mold is full, the top edges of the core and outer shell being exactly on a line.

If desired, the corrugated metal or wire-cloth may be dispensed with and the strips n be employed alone. In this case the metallic strips or pieces n , provided with projections, as described, may be made of sufficient length to go around the whole casket, and thus serve the double purpose of providing an attachment for the lid-fastening screws, and also of giving stiffness to the walls of the casket, and so avoid the use of the corrugated metal or wire-cloth, and at the same time prevent any liability to warping or springing of the upper edges of the side walls.

After the cement is set the core is extracted by folding in the ends of the collapsible sections, as before described, and removing them one at a time, the bottom section being jarred loose and lifted out last, the screws E in the bottom being first removed. The clamps D are then loosened and the walls of the outer shell removed, after which the holes left by the screws E are filled up with cement and the casket is completed.

If it is desired to embed a skeleton frame of iron and wood strips into the casket to add further to its strength, and to provide for support for the screws which fasten on the handles, such frame is placed in position upon the first layer of cement spread on the base-plate B, the subsequent proceedings being as described.

Having thus described my invention, what I claim as new, and desire to secure by Letters Patent, is—

1. In a coffin-mold, a collapsible core having end pieces hinged to the side walls of the core, and provided with suitable fastenings, substantially as and for the purpose described.

2. In a collapsible core for coffin-molds, the combination of the side pieces, $b b'$, hinged end pieces, $b' b''$, bars b^3 , staples e , and pins p , substantially as shown and described.

3. A core for coffin-molds, having one or more openings, o , formed in its bottom, and adapted to be closed by corresponding pieces, o' , substantially as and for the purpose described.

4. In a coffin cast of cement or other plastic material, the metallic pieces or strips n , of any suitable dimensions, and having lateral projections $n' n'$ for the purpose of strengthening the upper part of the casket and affording an attachment for the lid-fastening screws, substantially as described.

5. A burial-casket composed of cement or other plastic material, and having the inside of its walls corrugated, or formed with one or more depressions, whereby the weight of the casket is diminished without impairing its strength or affecting its external finish, substantially as described.

6. In a mold for burial-caskets, a core having

in its bottom one or more openings, whereby the surplus cement or other plastic material may be readily removed, substantially as described.

5 7. In a mold for burial-caskets, the sectional core C, composed of the parts s s' s², having side walls, b b, and end walls, b' b², provided with suitable fastenings, the lower section being provided with a bottom having longitudinal openings o o, adapted to be closed by corresponding strips, o' o', substantially as shown and described.

8. The combination of the outer shell, A, having base-plate B, the core C, the compound 15 pins or screws E, composed of the parts f f,

adapted to extend through the bottom of the casket for the purpose of supporting the core, and the adjustable end clamps, D, composed of screw-threaded rods e e', connected by couplings e², one of said rods being hinged to one of the side pieces of the mold, and the other adapted to fit in a slot formed in the other side, substantially as shown and described. 20

In testimony whereof I affix my signature in presence of two witnesses.

CHARLES E. WILSON.
